WITNESSED:

UNITED STATES PATENT OFFICE.

WILLIAM MORRISON, OF BALTIMORE, MARYLAND.

DESIGN FOR A TOY BANK.

Application filed January 7, 1924. Serial No. 8,269. Term of patent 3½ years.

To all whom it may concern:

Be it known that I, WILLIAM MORRISON, a citizen of the United States of America, residing at Baltimore, in the county of Baltimore and State of Maryland, have invented a new, original, and ornamental design for Toy Bank, of which the following is a specification, reference being had to the accompanying drawings, forming a part hereof.

The figure is a perspective view showing my new, original and ornamental design for toy bank.

I claim:—

The ornamental design for a toy bank as shown.

WILLIAM MORRISON.
